UNITED STATES PATENT OFFICE.

CAROLINA FUCHS-MAURER, OF ZURICH, SWITZERLAND.

HAIR-ONDULATOR.

1,398,637.

Specification of Letters Patent. Patented Nov. 29, 1921.

Application filed April 6, 1920, Serial No. 371,720. Renewed April 9, 1921. Serial No. 460,095.

To all whom it may concern:

Be it known that I, CAROLINA FUCHS-MAURER, a citizen of Germany, and a resident of Zurich, Switzerland, have invented 5 new and useful Improvements in Hair-Ondulators, of which the following is a specification.

This invention relates to hair ondulators of the cross-lever type, and it consists in 10 the arrangement of a fixed tube on one lever arm and of a pair of gyratory tubes on the other lever arm, said pair of tubes being fitted with rigid trailers or feelers under spring action and controlled by the 15 first mentioned tube so as to close around the latter by an eccentric movement around their pivots. The said tubes may be replaced by other forms of rods, fingers or bars.

20 To render my invention clear, I will describe the same fully with reference to the accompanying drawings, in which:

Figure 1 is an elevation, shown as a perspective view, of an embodiment of my 25 novel ondulator in the open condition. Figs. 2 and 3 being cross-sections of the tubular fingers showing same respectively partly closed and fully closed.

In the example shown in Fig. 1, the shear- 30 arm a carries a pair of cylindrical tubular fingers b , while the arm a^1 holds a fixed finger c . The fingers b are mounted so as to swing around parallel axes or pivots d connected firmly together with their upper 35 portions. The pivots d may be at the exterior of or within the fingers b in a position to cause the latter to move eccentrically with relation to their own axis. The fingers b carry fixed trailers or feelers e pro- 40 vided at or near the upper end, while at the lower end their is provided for each finger b a stop f fast on the arm a . Each finger b carries a pin g that rests against the stop f when the finger is in an open 45 position as shown in Fig. 2, and is kept there by a torsion spring h which presses its upper end against the pin g . A heating

device, being a well known feature, is not shown so as to keep the drawing clear.

The operation is as follows:—

The ondulator is properly heated and the hair is placed in the space between the fingers b and c , after which the handles a, a^1 are pressed toward one another, thereby causing the fixed finger c to enter midway 50 between the pivoted fingers b and contact with the trailers e of the latter as shown in Fig. 2. The letter M denotes a strand of hair entwined on the fingers b and c . Continued pressure on the handles a, a^1 55 causes further penetration of the finger c past the fingers b toward the rear thereof until the ondulator becomes fully closed as shown in Fig. 3. In this last closing move- 60 ment the finger c presses against the trailers 65 e and, forcing them rearward, they bring about the turning motion of the fingers b on their pivots d in opposition to the retaining action of the springs h , the fingers b , gyrat- 70 ing around the finger c , being brought 70 against each other in front of said finger c . The hair now lies in a practically complete circle around the finger c . At opening the ondulator, the finger c pushes back the fingers b and the springs h return and retain 75 the latter in the fully open position against the stops f .

I claim:

1. A hair ondulator comprising a two- 80 armed handle, a fixed finger on one handle arm, a pair of separated pivoted fingers on the other handle arm, eccentrically disposed pivots for and trailers on the said pivoted fingers, resilient means for opening the latter, and stops on the handle arms to limit 85 the opening movement of said pivoted arms.

2. A hair ondulator comprising a two- 90 armed handle, a fixed finger on one handle arm, a pair of pivoted fingers on the other handle arm, means whereby the fixed finger moves the pivoted fingers into a rearward closing position, and means for opening the pivoted fingers to a limited extent.

CAROLINA FUCHS-MAURER.
